UNITED STATES PATENT OFFICE

114,447

DESIGN FOR A NOVELTY PIN

Winifred M. Gustin, Winchester, Mass.

Application November 9, 1938, Serial No. 80,975

Term of patent 3½ years

To all whom it may concern:

Be it known that I, Winifred M. Gustin, a citizen of the United States, residing at Winchester, in the county of Middlesex and Commonwealth of Massachusetts, have invented a new, original, and ornamental Design for a Novelty Pin, of which the following is a specification, reference being had to the accompanying drawing, forming a part thereof.

Fig. 1 is a front elevation of the pin showing my new design, and

Fig. 2 is a side elevation thereof.

I claim:

The ornamental design for a novelty pin, substantially as shown.

WINIFRED M. GUSTIN.
